UNITED STATES PATENT OFFICE.

CHARLES PHILO MOSHER, OF GROTON, NEW YORK, ASSIGNOR TO CORONA TYPEWRITER COMPANY, INC., A CORPORATION OF NEW YORK.

TYPE-WRITING MACHINE.

1,269,201.

Specification of Letters Patent. Patented June 11, 1918.

Application filed November 27, 1915. Serial No. 63,736.

To all whom it may concern:

Be it known that I, CHARLES PHILO MOSHER, a citizen of the United States, and a resident of Groton, county of Tompkins, 5 and State of New York, have invented certain new and useful Improvements in Type-Writing Machines, of which the following is a full, clear, and exact description.

This invention relates more particularly 10 to the case shift of foldable visible front-strike typewriting machines such as disclosed in my application Serial No. 56,242, filed October 16th, 1915, which has matured into Patent 1,222,443, dated April 10, 1917. 15 One of the principal objects of the invention is to provide simple and efficient means whereby the type basket may be given movement relatively to the platen to adapt the type blocks or heads to have a plurality of 20 characters thereon, and so to construct and arrange the shift mechanism that it may be folded toward the platen when not in use, in order that the machine may be made compact for transportation and other purposes. 25 Another object of the invention is to mount a shift mechanism upon a foldable support which also serves as a means for mounting the key action and type-bars, and which shift mechanism, key action and type-bars 30 may be moved with the support to a position to materially reduce the cubical dimensions of the machine when not in use and make the machine when in a compact condition of a substantially uniform shape convenient for carrying purposes. 35

A further object of the invention is to provide simple and efficient means whereby considerable leverage is obtained at the initial depression of the shift lever in order 40 that the type basket may be readily elevated.

Other objects of the invention are to provide simple and efficient mechanism which may be located at opposite sides of the machine to adapt the case shift to be operated 45 from either side thereof; to provide means whereby anti-friction devices may be employed to assist in the easy operation of the shift mechanism; and to provide simple and efficient means for locking the shift lever.

50 A still further object of the invention is to provide a case shift mechanism which is simple in construction and which may be readily made and assembled.

With these and other objects in view, the 55 invention will be hereinafter more particu-

larly described with reference to the accompanying drawings, which form a part of this application and will then be pointed out in the claims at the end of the description.

In the drawings, Figure 1 is a longitudinal 60 section, partly in elevation, of one form of machine embodying the invention, showing in side elevation a part of the key action in addition to the shift mechanism.

Fig. 2 is a vertical section partly in elevation of the case shift mechanism. 65

Fig. 3 is a view similar to Fig. 2, except that the shift lever has been depressed to elevate the type-bar basket.

Fig. 4 is a fragmentary plan view of one 70 side of the platen shift and key action support.

Fig. 5 is a fragmentary transverse section taken on the line V—V of Fig. 4.

Fig. 6 is a transverse section taken on the 75 line VI—VI of Fig. 4; and

Fig. 7 shows a modified form of shift mechanism.

While the invention is shown as applied to a typewriter in which an inclosing case is 80 employed, and in which the type-bar basket is shifted, it will be understood that the invention may be used in writing machines wherein the usual or any preferred form of frame or parts may be employed, or wherein 85 the platen or platen carriage is shifted instead of the type basket.

The inclosing case 10 may be of any suitable construction and forms the main supporting means for the different parts of the typewriter and is so constructed that when the case is closed all of the operating parts of the typewriter are inclosed within said case. As shown, the case 10 has a main member 11, the latter having a base 12, sides 90 13 and a rear wall 14, to the upper end of which rear wall is hinged at 15 a top or cover 16. At 17 is a foldable case member which is hinged at 18 to the base or wall 12 of the main member 11, and is adapted 95 to be moved upwardly and rearward toward the platen and against the forward edge of the sides 13 so that when the top or cover 16 is moved forward on its hinge 15 a substantially uniform and box-like package is provided. The foldable case member is provided with lugs 19 located on opposite sides of said member 17 and pivoted to each lug is a stay 20. The stay 20 is provided with a slot 21 and is normally forced 100

in one direction by a spring 22, said slot 21 being curved at its upper end, as at 23, to adapt the shank of a button or stud 24 to pass therethrough, so that when the stays 5 are in the position shown in Fig. 1 the foldable case member 17 will be held in its unfolded position but when the stays are pressed against the tension of the springs 22 such action will place the shanks of the 10 studs 24 in alinement with the main part of the slots 21 and the member 17 may be moved to its folded position. Instead of the stays any other means may be employed for holding the member 17 in either its folded 15 or unfolded position.

A platen carriage 25 is adapted to travel transversely of the machine, there being suitable tension means and escapement mechanism, not shown, for this purpose. 20 The carriage has a base 26 vertically disposed and has its horizontal edges grooved and opposed to grooves in plates or guides 27 and 28. The plates 27 and 28 are secured to a plate 29 held to the rear wall 14 of the main member 11, and the grooves of said plates and of the carriage base 26 form raceways for anti-friction devices, as balls 30, to adapt the carriage to move easily during the letter-spacing movement thereof. 25 The carriage 25 may have end walls 31 in which is rotatably mounted the usual roll or platen 32, there being a paper apron, as 33, as well as other features which usually form a part of the carriage or coöperating means 35 therefor.

A foldable support 34 is pivotally held on a rod 35 which extends transversely of the machine between the sides 13 of the main casing member 11. This support 34 has 40 sides 36 which may be connected by a transversely extending bar 37, and each side is connected by a link 36^a to the foldable case member 17 to foldably hold the outer end of the support 34 in its normal operative position. At the forward ends of the sides 36 are arranged vertical guides 38 having grooves which are opposed to grooves in the ends of a type-bar segment or support 39. The grooves of the guides 38 and the 45 grooves in the ends of the segment 39 form raceways for anti-friction devices, as rolls 40, to adapt the type-bar segment to be easily moved vertically as will be presently described. The segment 39 is provided with 50 slots 41 and in each slot is pivotally held a type-bar 42, a curved rod 43 being suitably held in the segment to serve as pivotal means for the type-bars. The type-bars at their outer ends have a type-head or block 44 on 55 which are the type 45 representing upper and lower case characters, etc. The type-heads or blocks are adapted to rest upon a cushion, as 46, which is supported upon a curved plate 47, the latter being held to 60 the outer ends of rods 48 which project for-

wardly and which are secured at their rear ends to the segment 39.

Each type-bar has a lug to which is pivoted at 49 one end of a link 50, said link being pivoted at 51 at its forward end to a bell-crank lever 52. The bell-crank lever 52 has a downwardly extending end 53, one edge, as 54, of which is curved to provide a cam surface which is adapted to be engaged by the cam edge 55 of a lip or extension 56 75 of a key-operated lever 57. The key-operated lever 57 is provided with a key 58 by which the said lever may be operated. Only one key-lever, bell-crank lever and type-bar are shown, but the usual number of such 80 parts may be employed and such parts may be arranged in groups or banks in order that a substantially uniform touch may be obtained. As shown, it is intended that there should be four groups or banks of key-operated levers 57, and a corresponding number of bell-crank levers 52, the latter being pivotally mounted on rods or supports 59 while the key-operated levers 57 are pivotally mounted upon supports 60, said supports 60 90 being arranged horizontally when the machine is in its normal operative position and vertically disposed under the rods or supports 59. The rods 59 and 60 may be supported in plates 61 spaced by means of studs 95 62 or otherwise from the sides 36 of the foldable support 34, or said rods may be mounted in the sides direct. The parts thus far described may be substantially the same as that disclosed in my pending application 100 Serial No. 56,242, hereinbefore referred to, or may be of any other desired construction.

As a means for shifting the entire type-bar basket including the segment, type-bars, and supporting frame for the type-bars, elevating means may be employed at either or at both sides of the machine. A shift lever 63 may be located at each side of the machine and connected or not as preferred to move in unison, though as shown it is intended that the levers and parts operated thereby when located on both sides of the machine shift the type-basket independently. Each shift lever 63, where more than one is used, is provided with a key 64, and is 115 pivoted at 65 to one of the sides 36 of the foldable support 34. A supplemental lever 66 is located under the shift lever, and this lever 66 is provided with an enlarged part 67 having an outwardly projecting end or 120 portion 68, the upper edge of which is adapted to engage the under edge of the shift lever 63. The lever 66 has a curved portion 69 serving as a rocker which is adapted to roll or move on rolls 70. These 125 rolls 70 are grooved to assist in holding the levers 66 in position, and said rolls 70 are guided upon a curved track 71 forming the upper edge of a plate, support or member 72. The head 67 of the lever 66 is slotted 130

as at 73 and passing through the slot is the body of a screw or bolt 74, serving to hold the lever 66 to the side 36 of the support 34, yet permitting said lever to have a limited 5 bodily and lengthwise movement. At the outer end of the head 67 of the lever 66 is a curved end or lip 75 which is adapted to engage under a projecting lug 76 carried by the segment 39, the weight of the type basket being counterbalanced by a spring 77, one end of which is fastened to the lug 76 and the other end to a pin or bolt 78 projecting outward from the guide ends 38 of the support 34. A stop 79 is located on one 10 side of the lug of each supplemental lever 66 and a second stop 80 on the other side. The stop 80 is normally engaged by the lug 76 and determines the lower case position of the type, while the stop 79 when engaged 15 by the lug limits the upward shift movement of the segment and type basket, and therefore determines the position of the type with respect to the platen while the upper case type are being used.

20 It will be evident, upon a depression of either lever 63, where more than one is used, that during such depression the supplemental lever 66 will be moved by reason of its engagement with the lower edge 25 of the shift lever 63. The supplemental lever 66 when moved by the lever 63 will cause the end 75 to engage the projecting lug 76 and elevate the segment and type basket, and on the release of the shift lever 30 63 the parts will return to their normal position as shown in Fig. 2. It will be further evident that at the initial point of depression of the lever 63 the power arm of the supplemental lever 66 is much greater than 35 at the end of the depression and will make the elevation of the type basket easy to accomplish, and as the lever 63 continues to be depressed there will be substantially a 40 rocking action and a shifting of the point 45 of contact between the supplemental lever 66 and the shift lever 63 toward the fulcrum of said lever 63. This increases the speed of the shift movement of the type basket as the depression of the shift lever 50 63 increases, and at the same time the supplemental lever 66 shifts its position so as 55 to rock and move on the anti-friction devices 70.

Either or both of the shift levers 63, where 55 more than one is used, may be locked in the depressed position when it is intended to use the upper case characters for any length of time. As one means, a lock lever 81 is provided. This lever 81 is substantially 60 bell-crank shaped and is pivoted at 82 to the shift lever 63. The lock lever 81 is normally forced in one direction by means of a spring 83, one end of which is attached to said lever 81 and the other end to the shift 65 lever 63, the spring 83 serving to force the

lock lever 81 in one direction and to an engaging position, there being a spring 84 provided to assist in maintaining the lever 63 in its normal position particularly when the support 34 is moved to its folded compact position. One arm, as 85, of the bell-crank lever 81 is provided with a key 86 and the other arm 87 of said lever 81 is notched so as to engage, when the lever 63 is depressed, with a substantially rectangular lug 75 or boss 88, serving thereby to hold the lever 63 in its depressed position. By releasing the lever 81, the lever 63 and parts operated thereby will be restored to their normal position by reason of the weight of the parts 80 shifted, though one or more springs may be employed to assist in this operation if necessary or desired.

In Fig. 7, a construction is shown wherein the supporting rods 59 for the bell-crank 85 levers 52 of the key action and the supporting rods 60 of the different groups of key-operated levers 57 are supported in the sides 36 of the foldable support 34 instead of in separate plates spaced from said sides 36. 90 In this construction the shift lever 89 and the lock lever 90 are substantially the same as the construction shown in Figs. 1 to 6 inclusive. The shift lever 89 has its lower edge adapted to engage the arm 91 of a 95 lever 92. This lever 92 is pivoted at 93 and has its rear end 94 adapted to engage under the lug 95 to move the type-bar basket for case shift, there being two stops 96 and 97 similar to the stops 79 and 80 for positioning the type basket both in its normal and shifted positions, as already described. As with the other construction the shift means or part thereof may be duplicated at the other side of the machine.

100 From the foregoing, it will be evident that simple and efficient shift mechanism is provided; that said shift mechanism adapts the type basket to be moved with comparatively little force; that the shift mechanism is 110 so mounted as to be foldable into compact relation to the platen carriage; that said shift mechanism is adapted for use in various forms and constructions of typewriting machines; and that said shift mechanism may 120 be readily made and assembled.

Having thus described my invention, I claim as new and desire to secure by Letters Patent:—

1. In a typewriting machine, the combination of supporting means, a carriage adapted to travel along said supporting means, a type segment, a shift lever, a supplemental lever having a rocking and bodily lengthwise movement and a shiftable point 125 of engagement with the shift lever to vary the speed of movement of said lever, means whereby the supplemental lever may be caused to shift the type basket, means for determining the position of the type basket 130

- in its normal and shifted positions, and locking means for holding the shift lever in its shifted position.
2. In a typewriting machine, the combination of a case-shift support, a key-operated shift lever, and a supplemental lever having a rocking and shiftable engagement with the shift lever and adapted to move said support.
- 10 3. In a typewriting machine, the combination of a case-shift support, a key-operated shift lever, a supplemental lever having a rocking and bodily lengthwise movement and a shiftable engagement with the shift lever and adapted to shift said support, means for determining the position of the type segment in its normal and shifted positions, and locking means for holding the shift lever in its shifted position.
- 20 4. In a typewriting machine, the combination of shift-supporting means, a shift lever, and a rocking and bodily slideable supplemental lever having a shifting rocking engagement with the shift lever and a shifting fulcrum and adapted to move said shift-supporting means.
5. In a typewriting machine, the combination of a foldable support, a platen carriage, a type segment mounted on the foldable support, and case-shift mechanism also mounted on the support.
- 30 6. In a typewriting machine, the combination of a foldable support, a platen carriage, a type segment mounted on the support, and shift mechanism for the type segment also mounted on the support and partaking of its folding movement.
7. In a typewriting machine, the combination of a normally stationary support, a platen carriage movable along said support, a foldable support pivotally held to the stationary support, a type segment mounted upon said foldable support, and shift mechanism operatively connected to the type segment to shift the segment and mounted upon the foldable support to partake of its folding movement.
8. In a typewriting machine, the combination of a normally stationary support, a platen carriage movable along said support, a foldable support pivotally held to the stationary support, a type segment, and case shift mechanism mounted entirely upon the foldable support to partake of its folding movement.
- 55 9. In a typewriting machine, the combination of a foldable support, a type segment mounted on the support, a platen carriage, a shift lever mounted on the support, a supplemental lever mounted on the support and having a shifting rocking engagement with the shift lever, and operating connections between the supplemental lever and type-segment for moving the segment when the shift lever is actuated.
10. In a typewriting machine, a platen, type, a pivoted key-operated shift lever, and a supplemental rocking bodily movable lever having a shiftable rocking connection with the shift lever and adapted to impart a relative shift movement to the type and platen.
- 70 11. In a typewriting machine, a platen, type, a pivoted key-operated shift lever, a support, and a supplemental lever having a relative and bodily moving rocking connection with the shift lever and the support.
12. In a typewriting machine, a case-shift support, a pivoted key-operated shift lever, a second support, a supplemental lever having a relative bodily moving and rocking connection with the shift lever and the second support, said supplemental lever having a power arm that decreases during the depression of the key, the power arm of the shift lever increasing during the same depression.
- 80 13. In a typewriting machine, a platen, type, a support, and two levers operated by a key and having a relative rocking and bodily moving connection with each other, one of said levers having a similar connection with the support, said levers having relatively changing power arms during the depression of said levers.
- 90 14. In a typewriting machine, the combination of a support, a carriage adapted to move along said support, a foldable support pivoted to the first-mentioned support and adapted to be moved from a normal open position to a compact position relatively to the platen carriage, said foldable support having guides, a segment vertically movable in said guides, a spring normally counter-balancing the weight of the segment, rods extending forwardly from the segment, a plate held to said rods, a cushion supported by the plate, type-bars pivotally held to the segment and having their ends supported by the cushion in a normal position, means for operating the type-bars, a lug carried by the segment, stops arranged on opposite sides of the lug to position the segment in its normal and shifted positions, a shift lever, a supplemental lever having a shiftable connection with the shift lever and having one end thereof adapted to engage the lug of the segment to adapt the segment to be elevated when the shift lever is depressed, and means for locking the shift lever in its depressed position.
- 100 15. In a typewriting machine, the combination of a support, a carriage adapted to move along said support, guides, a segment vertically movable in said guides, rods extending forwardly from the segment, a plate held to said rods, a cushion supported by the plate, type-bars pivotally held to the segment and having their ends supported by the cushion in a normal position, means for operating the type-bars, a lug carried by the
- 110 115 120 125 130

- segment, stops arranged on opposite sides of the lug to position the segment in its normal and shifted positions, a shift lever, and a supplemental lever having a shiftable connection with the shift lever and having one end thereof adapted to engage the lug of the segment to adapt the segment to be elevated when the shift lever is depressed. 50
- 5 16. In a typewriting machine, the combination of a support, a carriage adapted to move along said support, a vertically movable segment, type-bars pivotally held to the segment, means for operating the type-bars, a lug carried by the segment, stops arranged on opposite sides of the lug to position the segment in its normal and shifted positions, a shift lever, and a supplemental lever having a connection with the shift lever and having one end thereof adapted to engage 55 the lug of the segment to adapt the segment to be elevated when the shift lever is depressed. 10
- 15 17. In a typewriting machine, the combination of a support, a carriage adapted to move along said support, a foldable support pivoted to the first-mentioned support and adapted to be moved from a normal open position to a compact position relatively to the platen carriage, said foldable support having guides, a segment vertically movable in said guides, type-bars pivotally held to the segment, means for operating the type-bars, and case shift mechanism mounted on the foldable support. 20
- 25 18. In a typewriting machine, the combination of a support, a platen carriage movable on said support, a type basket, a shift lever, a supplemental lever operated by the shift lever and adapted to move the type basket, said supplemental lever having a curved lower edge, a stationary curved track, and grooved rolls forming a support for the supplemental lever in its movement. 25
- 30 19. In a typewriting machine, the combination of a type segment support, a shift lever, and a supplemental lever adapted to lift said type segment support and having a shiftable point of connection with the shift lever and a shifting fulcrum. 35
- 35 20. In a typewriting machine, the combination of a type segment support, a pivoted shift lever, and a supplemental lever adapted to lift said type segment support and having a shiftable connection with the shift lever and the machine frame. 55
- 40 21. In a typewriting machine, the combination of a type segment support, a pivoted shift lever, and a supplemental lever adapted to lift said type segment support and having a shiftable point of connection with the shift lever and a sliding and rocking engagement with the machine frame. 60
- 45 22. In a typewriting machine, the combination of a type segment, a pivoted shift lever, a support, and a supplemental lever interposed between the shift lever and support and adapted to shift said type segment and having shiftable rocking contact with the shift lever and a sliding and rocking contact with the support. 65
- 50 23. In a typewriting machine, the combination of a type segment, a shift lever, a curved support below the shift lever, and a supplemental lever operatively connected to shift the type segment and having a curved lower edge, said supplemental lever being interposed between the curved support and the shift lever and adapted to have a rocking movement and a bodily lengthwise sliding movement imparted thereto by the shift lever. 70
- 55 24. In a typewriting machine, the combination of a type segment, a shift lever, a curved support below the shift lever, and a supplemental lever operatively connected to shift the type segment and having a curved lower edge, said supplemental lever being adapted to rock upon and slide bodily lengthwise relatively to said support and having a shifting rocking engagement with the shift lever. 80
- 60 This specification signed and witnessed this 20th day of November, A. D. 1915.
